Primary Examiner — Elizabeth J Oswecki

(57) **CLAIM**

The ornamental design for a sole for footwear, as shown and described.

DESCRIPTION

1. Sole for footwear

1.1 : Perspective

1.2 : Perspective

1.3 : Front

1.4 : Back

1.5 : Left

1.6 : Right

1.7 : Top

1.8 : Bottom

1 Claim, 8 Drawing Sheets
